A.H.S.

UNITED STATES PATENT OFFICE

GEORGES MAIN, OF PARIS, FRANCE

INCANDESCENT ELECTRIC LAMP

Application filed June 28, 1928, Serial No. 288,845, and in France July 26, 1927.

The invention relates to incandescent electric lamps of the vacuum or the gas type, and it has for its object to provide an improved lamp adapted to produce a uniform illumination upon the plane to be illuminated, or more generally, to provide a lamp having a polar curve of luminous intensity of the desired outline.

Attempts have been made to attain such results by surrounding the lamp by reflectors or glass diffusers provided with prisms, or reflectors of polished metal forming projectors, or further, by silvering or enamelling certain parts of the lamp. However, all such methods have proved insufficient, and the resulting efficiency was always low, since it is impossible to design reflectors of the proper shape in connection with an illuminant (incandescent filament) which differs much from a point source of light.

An incandescent electric lamp according to the invention comprises in combination a lamp bulb having an internal reflector whose shape is such that each point of the incandescent filament acts as a point source of light relatively to the adjacent surface of the reflector, (otherwise stated, the said reflector, instead of having a single optical centre, possesses a plurality of optical centers, the corresponding points of the filament being centered with respect thereto) and/or more outer reflecting members adapted to deflect the luminous rays emitted by said lamp toward the plane to be illuminated with such a concentration of luminous flux that the intensity of light in each direction is inversely proportional to the cube of the cosinus of the angle formed by said direction with the perpendicular to said plane. In this manner I am enabled to direct the rays of light in the proper direction, and also to concentrate the light in the desired proportion, i. e. I afford the optimum distribution of the light which corresponds to the uniform illumination of the surface to be lighted.

The invention further relates to a specific lamp of this kind, especially designed for the lighting of roads, streets, avenues, railway station platforms, and other rectangular surfaces of limited width.

Further characteristics of the invention will be specified in the following description.

In the appended drawings, which are given solely by way example:

Fig. 1 is a diagrammatic view showing the polar curve of a point illuminant, either alone or combined with an external reflector.

Fig. 2 shows the polar curve of a lamp with horizontal spiral filament of the known type.

Fig. 3 shows the polar curve of a lamp with saw tooth or zigzag filament.

Fig. 4 shows an incandescent lamp provided with an internal reflecting screen or reflector.

Fig. 5 shows the polar curve which is obtained by the use of an internal screen, said screen consisting of opal glass and having the shape of a half-torus.

Figs. 6 to 10 show the curves obtained with internal screens of various shapes.

Fig. 11 shows the combination of a lamp with "directed light", with an external reflector.

Fig. 12 is a view which shows the polar curves to be obtained in the longitudinal and transverse direction in order to provide for a practically uniform illumination upon a rectangular surface.

Fig. 13 is a section on the line 13—13 of Fig. 14, showing a lamp with "directed light", so provided with an external reflector for the lighting of elongated rectangular surfaces.

Fig. 14 is a side view of the same.

Fig. 15 is a sectional view on a larger scale of the reflector and lamp on the line 15—15 of Fig. 16, and

Fig. 16 is a sectional view of the lamp on the line 16—16 of Fig. 15.

Fig. 1 shows the polar curve P^1 of an illuminant which is supposed to be concentrated at a point O; this curve is a circle whose radius O A represents the mean spherical intensity, which has the same value according to the different angles 10° , 20° , 30° , etc., starting from the vertical.

If the said illuminant O is placed within a reflector such as R, of the standard type, this produces a new polar curve P^2 , wherein the luminous intensity at different angles, 100

such as 0° , 10° , 20° , 30° etc., is represented by the lines $O B$, $O C$, $O D$, $O E$.

Let it be supposed that the surface to be illuminated is a plane surface such as $X Y$, situated at a distance h from the illuminant O ; the value of the light at the points of incidence B' , C' , D' , E' of the rays whose inclination is 0° , 10° , 20° , 30° will be as follows:

$$\begin{aligned} 10^\circ \quad & \frac{O B}{h^2} \\ 10^\circ \quad & \frac{O B \cos^3 10^\circ}{h^2} = 0,955 \frac{O C}{h^2} \\ 15^\circ \quad & 20^\circ \frac{O B \cos^3 20^\circ}{h^2} = 0,83 \frac{O D}{h^2} \\ 15^\circ \quad & 30^\circ \frac{O B \cos^3 30^\circ}{h^2} = 0,65 \frac{O E}{h^2} \end{aligned}$$

If E_0 denotes the illumination desired on the working plane and if it is supposed that $E_0=1$ and $h=1$ meter, it is observed that, in order to obtain a uniform lighting at B' , C' , D' , E' , the luminous intensities must be:

$$25 \quad O B = 1 \quad O C = \frac{1}{0,955} \quad O D = \frac{1}{0,83} \quad O E = \frac{1}{0,65}$$

The desired polar curve of equal illumination on the plane to be illuminated is represented at P^3 in Fig. 1. It will be seen that this curve is very different from curve P^1 .

In the preceding considerations, it is supposed that the illuminant consists of a point, and that the polar curve is a circle, but, in the known lamps, the said curves have the shapes shown in Figs. 2 and 3. Such curves, as well as the curves P_1 and P_2 of Fig. 1, can only afford a uniform lighting when the surface to be illuminated is a sphere, which condition is never fulfilled in practice, since the surfaces to be illuminated are generally flat or have no pronounced relief.

A curve substantially coinciding with curve P^3 may be obtained by the combination with the electric bulb of internal and external reflectors of suitable shape and relative arrangement, as explained hereunder.

Fig. 4 shows a bulb having an internal reflector for use in the lamp according to the invention. 1 is the incandescent filament, which has or has not a spiral shape, and is arranged in a circle; 2 is the reflecting screen, which may consist of polished metal or opal glass, or may comprise reflecting prisms. It will be observed that, since the screen is well centered relatively to the filament 1, each point of said filament will act as a point source of light relatively to the corresponding part of the screen, whereby a well determined distribution of the light will be obtained. In other words, the luminous flux will be maximum in certain predetermined directions.

Such directions will be selected according to the particular application in view. Thus, in Figs. 5, 6, 7, 8, the internal re-

flector or screen (having respectively the shape of a half torus, of a lower quarter of torus, of an upper quarter of torus, and of a double cone) will provide for the maximum light at an angle of 70° – 75° from the vertical. 70 In the case of the known lamp with horizontal filament (Fig. 2) the maximum intensity is obtained at an angle of 30° with the vertical (radius $O C$) whilst, in the case of the spiral saw-tooth filament shown in Fig. 3, the maximum intensity is at 90° (radius $O A$). 75

Fig. 9 shows by way of example a modification in which the lamp with its reflector or screen is disposed for indirect lighting, the filament being entirely concealed by the lamp, 80 the blinding effect is eliminated.

Fig. 10 shows another arrangement of the screen for direct lighting.

Considering again the bulb with internal reflector shown in Fig. 4, the polar curve obtained with the said bulb is shown at P_4 in Fig. 11, and herein the maximum illumination is obtained at 55° . 85

By comparing this curve with the curve P_2 of Fig. 1, the improvement in the uniform illumination of the plane to be illuminated is clearly apparent. However, this effect may be still further improved by the use of external annular reflectors, so shaped and arranged as to practically obtain the curve P_3 95 (Figs. 1 and 11) which constitutes the optimum polar curve.

The method of designing such annular reflectors is as follows:

First, by photometry measures (according to the known methods of Rousseau, Bloch and others), I determine the luminous intensity in the various directions, and then the values of the elementary luminous flux in the different spherical regions comprised in the angles 0° to 10° , 10° to 20° , 20° to 30° etc. . . whence I deduce the total luminous flux of the lamp. 100

In the graphic representation, the intensity in the directions 0° , 10° , 20° , 30° , 40° , 50° is represented (in Fig. 11) by $O A$, $O B$, $O C$, $O D$, $O E$, $O F$. I now calculate the mean luminous flux per surface unit, which is $\Phi \div 4\pi$, and deduce the intensity to be obtained in the vertical direction (0°) which is the basis for determining curve P_3 . This is readily determined by the rule of the cube of the cosine above indicated, and I may now trace the curve P_3 for uniform lighting upon the operative plane; the calculated intensity of the light in the directions 0° , 10° , 20° , 30° , 40° , 50° should be $O A^1$, $O B^1$, $O C^1$, $O E^1$, $O F^1$. I then determine the elementary luminous flux corresponding to these intensities, that is I multiply such intensities by the area of the spherical zone (whose radius is one unit of length) corresponding to the directions 0° , 10° , 20° . . . etc., in consideration, comprised in a cone whose angle is for example $2 \times 60^\circ = 120^\circ$ (which is an arbitrary an-

gle). I now compare the theoretical flux thus calculated with the flux actually measured (by the methods of Rousseau, etc., as above explained) and I find that the actual flux contained in the upper hemispherical region above 60° should be added to the actual flux of the lower regions, in order to compensate for the deficiency of the latter with respect to the calculated theoretical elementary flux.

This method will be more clearly understood with the assistance of a numerical example:

The results of my photometric measures are as follows:

Direction	0	5°	15°	25°	35°	45°	55°	65°	75°	85°
Intensities in candles	0	0	15	70	118	208	360	208	140	125
Direction	95°	105°	115°	125°	135°	145°	155°	165°	175°	180°
Intensities in candles	130	150	151	151	152	152	148	148	118	0

This corresponds to vectors $O A$, $O B$, etc., in curve P_4 .

The corresponding fluxes, deduced therefrom are as follows:

Half-angle of the cone	0°	10°	20°	30°	40°	50°	60°	70°	80°
	to	to	to	to	to	to	to	to	to
	10°	20°	30°	40°	50°	60°	70°	80°	90°
Area in the sphere	0,095	0,283	0,463	0,628	0,774	0,887	0,992	1,057	1,091
Flux in lumens	0	4	32	74	162	324	206	148	136
Half-angle of the cone	90°	100°	110°	120°	130°	140°	150°	160°	170°
	to	to	to	to	to	to	to	to	to
	100°	110°	120°	130°	140°	150°	160°	170°	180°
Area in the sphere	1,091	1,057	0,992	0,897	0,774	0,628	0,463	0,283	0,095
Flux in lumens	142	159	150	186	118	95	68	33	0

The total flux is the sum of the elementary flux, that is 1987 lumens, and the means flux per surface unit is $1987 \div 4\pi = 159$ which corresponds to a theoretical intensity on the vertical equal to 159 candles at 1 meter (represented by $O A^1$).

The calculation by the rule of the cube of the cosine gives:

Directions	0°	5°	15°	25°	35°	45°	55°
$1 \div \cos^8$	1	1,015	1,11	1,34	1,82	2,84	5,28
Theoretical intensities	159	161	176	214	290	451	840

These intensities are represented by $O A^1$, $O B^1$, $O C^1$, etc.

The theoretical elementary fluxes deduced therefrom are:

Half-angle of the cone	0°	10°	20°	30°	40°	50°
	to	to	to	to	to	to
	10°	20°	30°	40°	50°	60°

Area in the sphere	0,095
Flux in lumens	15

The total flux is the sum, that is 1451 lumens. Since the actual measured flux is 1987, this corresponds to an efficiency of $1451 \div 1987 = 0,73$ for the external reflectors, which is reasonable.

The comparison between the actual flux and the theoretical flux to be obtained is shown hereunder:

Conical regions	0-10	10-20	20-30	30-40	40-50	50-60
Flux of the lamp alone	0	4	32	74	162	324
Theoretical flux of the optimum lamp	15	50	99	182	350	735
Differences	15	46	67	108	188	431

The differences represent the deficiency in flux for the lower conical regions.

The external reflectors of the lamp should be so designed as to deflect into the lower

spherical regions the flux of the upper regions in order to compensate as exactly as possible such deficiency.

In the present example, the maximum intensity of the lamp without external reflectors being emitted at 55° (Fig. 11) I will obviously place the lower edge of the lowermost reflector E_1 above the 55° radius, for example on the radius 60° .

Suppose I desire to provide three reflectors or screens E_1 , E_2 , E_3 and that the lowermost screen E_1 is arranged to intercept the flux emitted in the region $60-80^\circ$, that is $206 + 148 = 354$ lumens, the second screen intercepting the flux in the region $80-110^\circ$, that is

$136 + 142 + 159 = 437$ lumens, and the uppermost screen intercepting the flux in the region $110-180^\circ$, that is

$$150 + 136 + 118 + 95 + 68 + 33 = 600$$

lumens. The screens will thus intercept $354 + 437 + 600 = 1391$ lumens, while the total deficiency of the lower cone whose angle is 120° is $15 + 46 + 67 + 108 + 188 + 431 = 855$ lumens, that is an efficiency of

$$855 \div 1391 = 0,62$$

for the screens.

I then distribute the 855 necessary lumens between the three screens in proportion to the flux which they intercept (354, 437, 600) that is: the screen E_1 will reflect

Half-angle of the cone	0°	10°	20°	30°	40°	50°
	to	to	to	to	to	to
	10°	20°	30°	40°	50°	60°

$354 \times 0,62 = 220$ lumens, the screen E_2 will reflect $437 \times 0,62 = 270$ lumens, the screen E_3 will reflect $600 \times 0,62 = 375$ lumens.

If the screen E_1 is arranged to reflect the light in the region $0-30^\circ$, it will largely compensate for the deficiency of this region ($15 + 46 + 67 = 128$). The screen E_2 is arranged to reflect the light in the region

Conical regions	0-10	10-20	20-30	30-40	40-50	50-60
Flux of the lamp alone	0	4	32	74	162	324
Theoretical flux of the optimum lamp	15	50	99	182	350	735
Differences	15	46	67	108	188	431

$30-50^\circ$, thus almost entirely compensating for the deficiency therein ($108 + 188 = 296$), and the screen E_3 is arranged to reflect the light in the region $50-60^\circ$, thus almost com-

pletely compensating for the deficiency therein (431). In fact screen E_1 is somewhat too large and screens E_2 and E_3 too small but the approximation is quite sufficient in practice.

The upper edge 4 of screen E_1 is thus located on the 80° radius, at a suitable distance from the lamp in order to prevent overheating of the screen and to keep the size of the apparatus within reasonable limits. Its lower edge 5 is at the intersection of the radius 60° with the first ray R reflected at 30° by the second screen E_2 (in order not to intercept said ray) at point $4a$, situated at a suitable distance from the lamp on the radius 110° . The tangent to the screen at the different points is the perpendicular to the bisectrix of the angle formed by the incident and reflected rays. The intermediate points and tangents are determined by dividing the incident cone $60-80^\circ$ and the reflected cone $0-30^\circ$ into an equal number of elementary regions.

The upper edge of screen E_2 being at $4a$ on the radius 110° , its lower edge is at the intersection of the first ray R^1 reflected at 50° by screen E_3 at point $4b$ situated at a suitable distance from the bulb on the radius 165° (the last ray having an appreciable intensity). The several points and tangents of screen E_2 are obtained as for screen E_1 .

Screen E_3 will extend from point $4b$ to a suitable point of the radius 110° , such as to keep the size of the apparatus within the desired limits and by taking account of the general shape of the curve constructed point by point, with the tangents, as explained with reference to screen E_1 .

It will be observed that the use of the lamp with internal screen is essential for the economical distribution of the light upon the plane to be illuminated for the following reasons:

(a) The screen 2 entirely occults the light with respect to the surface to be illuminated within a cone whose angle at the vertex is 40° . Since the amount of light to be reflected into the said cone in order to obtain a uniform illumination of the plane to be illuminated is very small (inasmuch as the illumination required in the vertical direction is only $1/8$ of the illumination required at 60° from the foot of the vertical) the screen E^1 which provides for the illumination on the plane to be illuminated between 0° and 30° will reflect only a small portion of the total luminous flux emitted by the illuminant.

(b) The screen 2 concentrates the rays emitted inwardly within the loop or circle formed by the filament, as shown in Fig. 4, and reflects these rays at a mean angle of 55° , that is in the direction (in the present example) where the maximum luminous flux is required.

65 The reflecting screens E^1, E^2, E^3 may consist

of polished or enamelled metal or of opal glass or silvered glass. The number and the shape of the internal and external screens shown in the drawings are given solely by way of example and may be varied as desired. The internal screen may be so arranged as to reflect the light emitted by the illuminant in any direction other than the one indicated in the drawings.

Obviously, the said screens may be secured in place in any suitable manner, and for instance by means of a fitting 6 mounted on the lamp, and provided with lugs 7, or in any other suitable manner.

Electric lamps such as herein described may be used as reflectors, or as diffusers for direct or indirect lighting.

In order to obtain a practically uniform illumination at all points of an elongated rectangular surface, the polar curves of luminous intensity should have the general shape shown in Fig. 12, in which 11 denotes the curve of luminous intensity longitudinally of the rectangle and 12 the curve of luminous intensity in the transverse direction.

The apparatus shown in Figs. 13 and 14, in which the said curves are obtained, comprises a trough-shaped external reflector 13 which is open at the bottom and is mounted on a vertical main body 14, secured to the cast iron cap 15 into which is screwed the tube 16 serving to support the apparatus.

The shape of the reflector has been specially designed to obtain the maximum spreading of the upper hemispherical luminous flux emitted by the lamp, as well as a distribution of the intensity according to curves 11 and 12. The said reflector may consist of an enamelled steel plate, or of polished, silvered or chrome-covered metal forming a mirror, or of silvered glass, or glass provided with reflecting prisms by which the light can be sent in the desired direction.

The trough-shape of the reflector shown in the drawings is given solely by way of example, and any other suitable shape may be employed.

The apparatus comprises a tube 17 slidable in the tube 16, in which it may be held at any point by a set screw (not shown); said tube carries at the lower part a socket 18, in which is mounted the lamp 19, so that the lamp filament can be vertically adjusted with reference to the external reflector.

Figs. 15 and 16 are views on a larger scale showing the arrangement of the lamp 19 and the reflector 13. A glass or metallic mirror 20 is placed in the lamp bulb below the said filament, and its shape is such that the light from filament 21 will be reflected in the proper direction.

As shown in Fig. 16, the mirror 20 comprises two oppositely disposed cylindrical reflecting surfaces, and the parts of the incandescent filament 21 of the lamp are parallel

with the respective faces of the reflector 20, so that each point of the said filament acts as a point source of light with respect to the adjacent portion of the screen; the filament 5 will thus occupy with reference to the reflecting screen a position offering a uniform distribution of the light upon the whole width of the screen, whereby the whole length of the incandescent filament will be 10 availed.

The filament 21 may consist of a continuous spiral, shunted to the electric circuit, or of two spiral parts mounted in parallel on the said circuit in such manner that if one 15 part should become broken, the illuminant would not be completely extinguished.

A screen 22, placed above the filament, serves to reflect a part of the light produced in the upper hemisphere of the electric lamp, 20 so that the light will not be absorbed by the main body 14 of the reflector 13.

The screen 22, as well as the screen 20, may consist of opal or silvered glass, or of glass comprising reflecting prisms, or of polished 25 metal which is silvered or covered with chrome to form a mirror, or like reflecting surface.

The shapes of the screens shown in the drawings are given solely by way of example, 30 and I may employ any other suitable shape.

From the preceding considerations it will be observed that, by the combination of the lamp 19 with directed light with the reflector 13, I obtain upon an elongated rectangle a 35 practically uniform illumination with a limited number of illuminants.

It is obvious that the details herein described and represented are given solely by way of example; for instance the shape of 40 the internal screen is not limited to the shapes illustrated in the drawing; its section may be plane, spherical, hyperbolic or the like. It may consist of opal glass, for example a double glass with the transparent part towards 45 the filament, the opal layer being more or less opaque according to the amount of light which is to pass through (diffused light), or it may consist of silvered or chrome-covered glass, or of glass covered with any reflecting 50 metal. It may also consist of reflecting prisms of glass, or of a polished metal mirror.

The shape of the filaments is not limited to the shapes represented in the drawings, and they may have a zigzag or a saw-tooth 55 shape, or the like. I may also employ several superposed filaments, or filaments placed in parallel layers, or filaments which are vertical or inclined from the vertical.

In like manner, the number and the position of the said screens in relation to the filament may also be varied at will.

Obviously, the present invention is not limited to the constructions herein described and represented, which have been given solely 65 by way of example.

Having now described my invention, what I claim as new and desire to secure by Letters Patent is:

1. In combination with an incandescent electric lamp having an internal reflecting member which is centered optically with respect to the filament and produces a concentration of the luminous flux in predetermined directions, external reflecting means adapted to deflect the luminous rays emitted by said lamp toward the plane to be illuminated with such a concentration of luminous flux that the intensity of light in each direction is inversely proportional to the cube of the cosinus of the angle formed by said direction with the perpendicular to said plane. 70

2. An incandescent electric lamp as claimed in claim 1, wherein said internal reflecting member is placed below said filament whereby it conceals the latter and directs the major part of the luminous flux upwardly, 80 said external reflecting means being placed above said filament.

3. An electric incandescent lamp for the illumination of an elongated rectangular plane 90 surface which comprises a bulb, a filament within said bulb having two incandescent portions whose general direction is parallel with the small sides of said rectangle, an internal reflecting member within said bulb, 95 having two symmetrical reflecting surfaces of cylindrical shape parallel with and facing said incandescent portions respectively and centered optically with respect thereto, whereby two main pencils of light, of determined inclination, are directed toward the small ends of said rectangle, and means, outside said lamp, for reflecting the remaining light toward said rectangle, whereby a uniform illumination of the latter is produced. 100

4. An electric lamp as claimed in claim 3, 105 wherein said reflecting means comprise an inverted trough-shaped reflector which is elongated in a direction at right angles to the incandescent portions of said filament.

5. An electric lamp as claimed in claim 3, which further comprises an upper reflector within said bulb and above said filament, for reflecting laterally the light emitted by the filament upwardly. 110

6. In an electric lamp as claimed in claim 1, means for adjusting the position of said lamp with respect to said external reflecting means. 115

7. In an electric lamp as claimed in claim 1, a rod slideable with respect to said external reflecting means for carrying said lamp, and means for securing said rod in adjustable position with respect to said external reflecting means. 120

In testimony whereof I have signed my name to this specification.

GEORGES MAIN.
